US00D919311S

(12) **United States Design Patent** (10) **Patent No.:** **US D919,311 S**
Jin (45) **Date of Patent:** **** May 18, 2021**

(54) **FOOTREST**

(71) Applicant: **SHENZHEN PRIME TECHNOLOGY CO., LTD**, Shenzhen (CN)

(72) Inventor: **Wenwu Jin**, Shenzhen (CN)

(73) Assignee: **SHENZHEN PRIME TECHNOLOGY CO., LTD**, Shenzhen (CN)

(**) Term: **15 Years**

(21) Appl. No.: **29/751,490**

(22) Filed: **Sep. 22, 2020**

(51) LOC (13) Cl. **06-01**

(52) U.S. Cl.

USPC **D6/349**; D6/601

(58) **Field of Classification Search**

USPC D6/334, 349, 353, 596, 601, 716, 716.6; D21/685, 686

CPC A47C 16/02-04
